Primary Examiner—Antoine Duval Davis
Attorney, Agent, or Firm—Senniger, Powers, Leavitt & Roedel[57] **CLAIM**

The ornamental design for an impact wrench, as shown and described.

DESCRIPTION

FIG. 1 is a right side elevation of an impact wrench of the present invention, the left side elevation being a mirror image of the right side elevation;

FIG. 2 is a front elevation of the wrench;

FIG. 3 is a rear elevation of the wrench;

FIG. 4 is a top plan of the wrench; and,

FIG. 5 is a bottom plan of the wrench.
